UNITED STATES PATENT OFFICE.

EVEREST A. BAYLIS, OF MADERA, MEXICO.

FEEDER FOR TUBE-MILLS.

960,782.

Specification of Letters Patent. Patented June 7, 1910.

Application filed January 25, 1909. Serial No. 474,086.

To all whom it may concern:

Be it known that I, EVEREST A. BAYLIS, a citizen of the United States, residing at Madera, in the county of Chihuahua, Mexico, have invented certain new and useful Improvements in Feeders for Tube-Mills; and I do hereby declare the following to be a full, clear, and exact description of the invention, such as will enable others skilled in the art to which it appertains to make and use the same.

This invention relates to tube mills and more especially to a feeder therefor.

With the present manner of feeding tube mills a complicated structure is necessary at the end of the mill in order to properly attach the feeder, moreover, the present feeders are all extremely liable to clog and the feed therefrom becomes uneven so that the mill is irregularly supplied with the sand.

The principal object of the present invention is to provide a feeder for tube mills which may be readily attached to any mill without materially affecting the construction of the mill and which will be free from clogging.

Another object of the invention is to provide a feeder for tube mills which will deliver a regular charge of sand to the mill upon every revolution thereof.

With the above and other objects in view, the invention consists, in general, of a feed pipe of peculiar form in combination with a trough adapted to hold the material to be fed to the mill.

The invention further consists in certain novel arrangements of parts hereinafter fully described, illustrated in the accompanying drawings and specifically set forth in the claim.

In the accompanying drawings, like characters of reference indicate like parts in the several views, and Figure 1 is a side elevation of a portion of a feed mill equipped with this invention. Fig. 2 is an end elevation thereof, a portion of the feed trough being broken away to show the lower part of the feeder.

The numeral 10 indicates the end of a tube mill and in this instance is shown the end opposite the driving mechanism which is not deemed essential here to be shown as the same is that common to all tube mills.

The tube mill 10 is provided with a hollow stub shaft 11 which is carried in bearings 12.

The feeder consists of a section of pipe, preferably about three inches in diameter, which has its end threaded as indicated at 13 and is securely screwed into the hollow stub shaft 11. The pipe extends for a short distance straight out from the stub shaft as shown at 14 and is then bent at right angles as indicated at 15. From this point, the pipe is bent in a spiral formed as indicated at 16 and there are preferably two turns used of the spiral. Situated below the plane of revolution of this spiral is a trough 17 so arranged that the end 18 of the spiral will pass through the trough at every revolution of the tube mill. This trough is supplied with the material to be fed to the mill in any desired manner.

When the mill is started the spiral revolves and at each revolution the end 18 dips into the material and takes up a charge thereof. This charge, by the action of gravity, constantly remains at the lower portion of the spiral and follows the same around until the straight section of pipe is reached. At this point it turns and flows directly into the tube mill. As soon as the end 18 has passed through the trough the remaining material flows in behind the end and is ready for the next charge to be picked up.

It will be observed that this device is absolutely free from all valves, pistons and other complicated apparatus liable to wear and become clogged. It will further be observed that, even if this device does become slightly clogged by some of the sand sticking to the sides when the mill is at rest, the action of the inflowing sand will automatically clean the same out.

As can be seen this device is of great simplicity and low cost of manufacture and by actual experiment it has been found that it requires a minimum of repairs.

There has thus been provided a simple and efficient device of the character described and for the purpose specified.

Having thus described the invention, what is claimed as new, is:

In combination with a tube mill, a hollow stub shaft supporting the same, and a feeder comprising a pipe of uniform cross sectional

area throughout its length and having a short section extending in alinement with said shaft and fixedly secured thereto whereby said pipe will revolve with said mill, and 5 a spiral forming a continuation of the short section arranged with its mouth in the direction of rotation of the tube mill.

In testimony whereof, I affix my signature, in presence of two witnesses,

EVEREST A. BAYLIS.

Witnesses:

A. R. MOREHOUSE,
A. R. WILLIAMSON.
